ATTYS.

UNITED STATES PATENT OFFICE.

OSCAR C. DAVIS, OF BROCKTON, MASSACHUSETTS.

SHOE AND OUTER-SOLE THEREFOR.

1,191,500.

Specification of Letters Patent. Patented July 18, 1916.

Application filed April 5, 1916. Serial No. 89,050.

To all whom it may concern:

Be it known that I, OSCAR C. DAVIS, a citizen of the United States, residing at Brockton, in the county of Plymouth and State of Massachusetts, have invented new and useful Improvements in Shoes and Outer-Soles Therefor, of which the following is a specification.

This invention relates to outer soles of 10 vulcanizable material such as rubber or a composition containing rubber, and to a shoe having an outer sole of vulcanizable material provided with a marginal portion projecting outside the upper, the upper side of 15 said marginal portion being exposed.

The object of the invention is to enable the exposed portion of the sole to simulate the welt of a welted shoe, so that although the sole and upper are united by means 20 other than the usual inseam stitches engaging a welt and an inner sole, the completed article will resemble a welted shoe.

The invention consists in the improvements which I will now proceed to describe 25 and claim.

Of the accompanying drawings forming a part of this specification: Figure 1 represents a perspective sectional view of the fore part of a shoe embodying my invention; Fig. 2 represents a fragmentary perspective view of a portion of the sole shown by Fig. 1; Fig. 3 represents a view similar to Fig. 2, showing a modification; Fig. 4 represents a fragmentary perspective view 35 of a portion of the finishing strip shown by Fig. 3.

The same reference characters indicate the same or similar parts in all the views.

In the drawings: My improved outer sole 40 comprises a body 12 of rubber or a composition containing rubber, and a marginal finishing strip 13, which is of vulcanizable material like that of the body, but is preferably of a composition susceptible to a better finish and is set into the marginal portion of the upper side of the body and suitably united thereto.

The finishing strip forms the portion of the upper side of the sole which, in the completed shoe, projects outside the upper 45 14, the upper sides of the body and strip being flush with each other, and the outer edge of the strip being preferably of less thickness than the body, and forming a part of 55 the edge of the sole, as shown by Figs. 1, 2 and 3.

The strip may be formed to simulate a welt having indented stitches, and as here shown has molded tapering transverse ridges formed in accordance with my patent 60 1,169,085.

The body and finishing strip may be united in any suitable way, preferably by vulcanization, said parts being prepared for vulcanization, assembled while in this 65 condition and subjected to vulcanizing heat and thereby united. If desired, however, the parts may be otherwise united, and may for example be vulcanized before they are assembled, and then united by a cold process 70 involving the employment of a cold vulcanizing or cementing fluid or material.

The finishing strip has a relatively wide inner or bottom face bearing on the corresponding recessed top face of the body, 75 these being hereinafter called reciprocal side bearing faces, affording a union of considerable area. Said union is preferably supplemented by complementary interlocking members or reciprocal edges on the strip and 80 body at an angle to the side faces. Said edge members may include the inner edge 18 of the strip, a shoulder 19 on the body, the walls of orifices 20 formed in the strip and the margins of studs 21 integral with the 85 body and entering the said orifices, all as shown by Figs. 1 and 2. The edge 18 may be beveled and the shoulder 19 undercut to overhang said edge. The orifices and studs may be omitted, and the inner edge 18^a of 90 the strip may be serrated, as shown by Figs. 3 and 4, and beveled to engage an undercut serrated shoulder 19^a on the body.

The finishing strip for each sole may be cut from a supply strip of indeterminate 95 length, and then fitted to and united with the sole body. The form of the upper side of the strip, causing it to simulate a stitched welt, may be expeditiously and advantageously imparted during the process of 100 making the strip. It would be a much more difficult and expensive operation to mold the marginal portion of the upper side of the body to produce the same effect, or in other words, to make the indented stitch-simulating surface integral with the body, in contradistinction to making it on a strip or veneer subsequently united to the body.

The sole and upper may be connected in any suitable manner, or by any suitable 110 means, such as stitches 22, which may also secure an inner sole 23, as shown by Fig. 1.

The finishing strip 13 may be provided with an inwardly projecting flange 24 of flexible material, such as duck or canvas, united by vulcanization or otherwise to the 5 strip and to the body 12. Said flange may be of suitable width to receive the stitches 22, and thus reinforce the stitch-receiving portion of the sole.

Having described my invention, I claim:

- 10 1. An outer sole comprising a rubber body having a recessed marginal top face and an edge face at the inner edge thereof, and a marginal finishing strip of rubber formed to simulate a welt and having bottom and inner edge faces integrally united respectively to the top and edge faces of the body, said parts forming an outer sole attached as one part to a shoe body and adapted to project therefrom with the said 15 finishing strip exposed.
- 20 2. An outer sole comprising a rubber body having a recessed marginal top face and an edge face at the inner edge thereof, and a marginal finishing strip of rubber formed to simulate a welt and having bottom and inner edge faces integrally united respectively to the top and edge faces of the body, said parts forming an outer sole at-

tachable as one part to a shoe body and adapted to project therefrom with the said 30 finishing strip exposed, the said edge faces being inclined and interengaged.

3. A shoe comprising an upper, an inner sole, and an outer sole composed of a rubber body having a recessed marginal top face and an edge face at the inner edge thereof, and a marginal finishing strip of rubber 35 formed to simulate a welt and having bottom and edge faces integrally united respectively with the top and edge faces of the rubber body, said outer sole being attached as one part to the inner sole, and its finishing strip being exposed at the exterior of the shoe.

4. An outer sole comprising a rubber 45 body and a marginal finishing strip set into the marginal portion of the upper side of the body and united thereto, said strip forming the marginal portion of the upper side of the sole, the finishing strip being provided with an inwardly projecting reinforcing flange united to the strip and body. 50

In testimony whereof I have affixed my signature.

OSCAR C. DAVIS.
